K. A. Duckman
ATTORNEY.

UNITED STATES PATENT OFFICE

JAMES C. GORDON, OF LOS ANGELES, CALIFORNIA

AIR CONTROL FOR INTERNAL COMBUSTION ENGINES

Application filed April 2, 1930. Serial No. 440,965.

This invention relates to an air control for internal combustion engines whereby varied quantities of air are admitted to the intake manifold of the engine as the quantity of fuel is varied in the carburetor.

An object of my invention is to provide a novel air control for internal combustion engines, the needle valve of which is connected to, and operable by the carburetor gas control lever.

Another object is to provide a novel means of regulating the amount of lift of the air control valve by a manually adjustable pivot.

A further object is to provide an air control of the character stated which is applicable to various types of engines.

Other objects, advantages, and features of invention may appear from the accompanying drawing, the subjoined detailed description, and the appended claims.

In the drawings:

Figure 1 is a transverse, sectional view of my control.

Figure 2 is a sectional view taken on line 25 2-2 of Figure 1.

Figure 3 is a side elevation of the control valve.

Figure 4 is a side elevation of my air control in operative position.

Figure 5 is a side elevation of a slightly modified form of pivot adjustment.

Figure 6 is a side elevation of still another form of pivot adjustment.

Referring more particularly to the drawings, the numeral 1 indicates a case which is suitably attached to a convenient part of the vehicle, such as the intake manifold. An air inlet port 2 is provided in the case 1. A fitting 3 extends from one side of the case 1 and a pipe 4 is coupled to the fitting and extends into the engine intake manifold 5. The air which passes out of the fitting 3 is controlled by a needle valve 6 which fits into a block seat 7 and the valve is slidably in the block. The block seat has a tapered seat 8 therein upon which the needle valve rests. A plurality of ports 9 are also provided in the block, the ports being above the seat 8 and as the needle valve is raised by a means to be further described, air passes through the

ports 9 and thence into the fitting 3 and to the intake manifold. The block 7 acts both as a guide and to prevent any foreign material from lodging on the seat 8.

A control rod 10 extends through the case 1 and is guided therein. A spring 11 bears against a head 12 thus normally holding the rod 10 in raised position. A nut 13 on the rod, limits the upward travel thereof. The rod 10 is moved simultaneously and synchronously with the accelerator lever 14 of the carburetor. The lever 14 may be controlled by either the hand or the foot.

A link 15 is pivotally connected to the lever 14 and to an operating lever 16, which lever is here shown as a bell crank, one end of which is attachable to the rod 10 and the link 15 is pivotally connected to the other end thereof. The lever 14 moves in the direction of the arrow in Figure 4 when the engine is accelerated.

A link 17 is pivotally secured at one end thereof to the rod 10 and the other end thereof is provided with an enlarged loop 18. The needle valve 6 is slotted as at 19 so as to receive the loop 18. A pin 20 extends through the valve and the loop bears against the pin to raise the valve when air is to be admitted to the manifold. A slot 21 is provided in the link 17 which communicates with the loop 18, and the throw of the outer loop and of the link is varied by the following means:

A block 22 is mounted upon a threaded adjusting bolt 23, said bolt being rotatable by a knurled head 24. A pin 25 projects from the block 22 into the slot 21 and the link pivots about the pin. It will be evident that as the block 22 is moved along the threaded bolt 23, that the throw of the outer end of the link will be varied. When the pin 25 is moved into the loop 18, there will be no appreciable movement of the throw end of the link, and consequently, no additional air will be admitted to the manifold. That is, the loop drops in the slot 19 and the pin 25 is at the top of the loop which is clear of the pin 20. Stops 26-26 are provided in the case 1 to limit the movement of the block along the threaded bolt.

Various other means may be employed to

adjust the block, namely that shown in Figures 5 and 6. In Figure 5 the block 27 is 5
slidable on a rod 28 and is manually adjusted by a push rod 29 which extends out through the wall of the case. In Figure 6, the block 10
30 is slidably mounted on a rod 31 and the ends of a cable 32 are secured to the block. The cable extends over sheaves 33—34, which 15
sheaves are pivotally mounted on the rod 31. One of the sheaves is exposed through the wall of the case so that it may be readily 20
rotated to adjust the block.

Having described my invention I claim:

1. An air control for internal combustion 15
engines, comprising a case, an outlet fitting 20
extending from the case, a valve adapted to 25
close said outlet fitting, a rod extending into 30
the case, a link pivotally secured to the rod, 35
a loop on the free end of the link, a pin ex- 40
tending through the valve and through the 45
loop, a block adjustably mounted in the case, 50
said link having a slot therein, a pin extend- 55
ing from the block into the slot, and manual 60
means to adjust said block relative to the 65
link.

2. An air control for internal combustion 15
engines, comprising a case, an outlet fitting 20
extending from the case, a valve adapted to 25
close said outlet fitting, a rod extending into 30
the case, a link pivotally secured to the rod, 35
a loop on the free end of the link, a pin ex- 40
tending through the valve and through the 45
loop, a block adjustably mounted in the case, 50
said link having a slot therein, a pin extend- 55
ing from the block into the slot, a threaded 60
bolt extending into the case, said block being 65
mounted on the threaded bolt and a 70
head on the bolt whereby it is rotated to 75
adjust said block.

3. An air control for internal combustion 15
engines comprising a case, an outlet fitting, 20
a seat in the case, a needle valve resting in 25
the seat whereby the outlet to the fitting is 30
controlled, a rod extending through the case, 35
spring means urging said rod into raised 40
position, a link pivotally secured to the rod, 45
the free end of said link being formed in a 50
loop, a pin extending through the needle 55
valve and through the loop, a block in the 60
case, said link having a slot therein extend- 65
ing to the loop, a pin extending from the 70
block into the slot, and manual means to 75
adjust said block relative to the link.

4. An air control for internal combustion 15
engines comprising a case, an outlet fitting, 20
a seat in the case, a needle valve resting in 25
the seat whereby the outlet to the fitting is 30
controlled, a rod extending through the case, 35
spring means urging said rod into raised 40
position, a link pivotally secured to the rod, 45
the free end of said link being formed in a 50
loop, a pin extending through the needle 55
valve and through the loop, a block in the 60
case, said link having a slot therein extend- 65
ing to the loop, a pin extending from the 70
block into the slot.

block into the slot, a threaded bolt extending 70
into the case, said block being mounted on 75
the threaded bolt, one end of said bolt pro- 80
truding from the case whereby it is rotated 85
to adjust the block.

In testimony whereof, I affix my signature.

JAMES C. GORDON.
